UNITED STATES PATENT OFFICE.

NERVE VAN POINDEXTER, OF ELKIN, NORTH CAROLINA.

RAIL-JOINT.

1,245,009.

Specification of Letters Patent. Patented Oct. 30, 1917.

Application filed March 7, 1917. Serial No. 153,013.

To all whom it may concern:

Be it known that I, NERVE VAN POINDEXTER, a citizen of the United States, residing at Elkin, in the county of Surry and State of North Carolina, have invented new and useful Improvements in Rail-Joints, of which the following is a specification.

This invention relates to rail joints and it consists in the novel features hereinafter described and claimed.

An object of the invention is to provide a rail joint of simple and durable structure having means for effectually connecting the adjacent ends of rail sections together whereby the said sections are restrained against movement with relation to each other and the securing bolts are relieved of much of the strain to which the joint is subjected when in use.

20 In one form of the invention the structure includes rail sections which are provided at their ends with recesses and tongues, the tongue of one rail section adapted to fit snugly in the recess of the next adjacent 25 rail section and vice versa. The said tongues and recesses are provided with beveled side walls and engaging enlargements which hold the rail sections against movement transversely and longitudinally with relation to each other. Securing bolts pass 30 through the said tongues and bear against the side portions of the adjacent rail sections whereby the parts are held in proper position with relation to each other.

35 In another form of the invention each rail section is provided at one end with a tongue and at its opposite end with a recess. The tongue of one rail section is adapted to fit snugly in the recess of the adjacent rail 40 section and these tongues and rail recesses are provided with enlargements and converging side walls and in the last mentioned structure securing bolts are also employed.

45 In the accompanying drawing:—

Figure 1 is a side elevation of the rail joint;

Fig. 2 is a similar view with parts in section;

50 Figs. 3 and 4 are perspective views of the adjacent ends of the rail sections;

Fig. 5 is a transverse sectional view of the rail joint taken on the line 5—5 of Fig. 2;

Fig. 6 is a similar view taken on the line 55 6—6 of Fig. 2;

Fig. 7 is a side elevation of a modified form of the rail joint;

Fig. 8 is a transverse sectional view of the form of rail joint as shown in Fig. 7. 60

In the form of the invention as illustrated in Figs. 1 to 6 inclusive, the rail joint comprises rail sections 1 and 2 which are provided at their bases with usual flanges and at their upper portions with usual heads. 65 The rail section 1 is provided at its end and at its upper portion with a tongue 3 having converging side walls. The tongue 3 is provided at its end with a cone-shaped enlargement 4. The rail section 2 is provided at 70 its end and in the vicinity of its upper edge with a recess 5 having converging side walls and which is adapted to snugly receive the tongue 3 of the section 1. The recess 5 is provided at its inner end with a cone shaped 75 enlargement 6 adapted to receive the enlargement 4 of the tongue 3. A bolt 7 passes transversely through the enlargement 4 and is provided at one end with a head which bears against the side of the said 80 enlargement and at its other end with a nut and washer which operate against the side of the rail section 2 as best shown in Fig. 2 of the drawing. The rail section 2 is provided at its end and in the vicinity of its 85 lower edge with a tongue having converging side walls and provided at its end with a cone shaped enlargement 9. The rail section 1 is provided with a recess 10 having converging side walls and provided at its 90 inner end with a cone shaped enlargement 11 adapted to receive the enlargement 9 of the tongue 8. A bolt 12 passes through the enlargement 9 and is secured in position in a manner as described in conjunction with 95 the bolt 7. The broader face of the tongue 8 upon the rail section 2 is at the opposite side of the said rail section from the broader face of the enlargement 3 upon the rail section 1, consequently in order to assemble 100 the rail section it is necessary to swing one of the rail sections with relation to the other whereby the tongues 3 and 8 may be inserted in their respective recesses and the enlargements 4 and 9 positioned in the enlargement 105 of the said recesses.

In the form of the invention as illustrated in Figs. 7 and 8, the rail sections 1' and 2'

are of the same general configuration as the rail sections 1 and 2 hereinbefore described. The rail section 1' is provided at its end with a recess 13 having converging side walls and which at its inner end is provided with a cone shaped enlargement 14. The rail section 2' is provided at its end with a tongue 15 having converging side walls and adapted to fit snugly within the recess 13 and the said tongue 15 is provided at its end with a cone shaped enlargement 16 adapted to fit snugly in the enlargement 14 of the recess 13. A bolt 17 passes transversely through the enlargement 15 and is secured in position in a manner similar to that described in conjunction with the bolt 7.

To assemble the rail sections 1' and 2' it is not necessary to swing one section with relation to the other but the said rail sections may be moved laterally with relation to each other when parallel whereby the tongue 15 and the enlargement 16 thereof are inserted in the recess 13 and the enlargement 14 thereof.

In both forms of the invention it will be seen that simple and durable structures are provided and that when the rail sections are connected with each other, the surfaces of the tongues and the grooves bear against each other whereby the securing bolts are relieved of much of the strain when the rail sections are in use.

Having described the invention what is claimed is:

1. A rail joint comprising a rail section 35 having at each end a recess provided with converging walls and having at its inner end a cone shaped enlargement, a second rail section provided at its end with a tongue having converging side walls and adapted to fit snugly in the said recess, the said tongue being provided at its end with a cone shaped enlargement adapted to fit snugly in the enlargement of the recess and a bolt 40 passing through the enlargement of the 45 tongue.

2. A rail joint comprising rail sections one of which is provided at its end and in the vicinity of its top side with a recess having converging side walls and provided 50 at its inner end with a cone shaped enlargement, said rail section also having at its end and below the said recess a tongue provided at its end with a cone shaped enlargement, the side walls of the said tongue converging toward each other, the other rail section being provided at its end with a recess and a tongue adapted to engage the first mentioned recess and tongue, and bolts 55 passing transversely through the enlargements of the tongues.

In testimony whereof I affix my signature.

NERVE VAN POINDEXTER.
